UNITED STATES PATENT OFFICE.

LEWIS C. MYERS, OF FREEPORT, NEW YORK, ASSIGNOR TO ROYAL TYPEWRITER COMPANY INC., OF NEW YORK, N. Y., A CORPORATION OF NEW YORK.

TYPEWRITING MACHINE.

Application filed February 12, 1925. Serial No. 8,791.

To all whom it may concern:

Be it known that I, LEWIS C. MYERS, a citizen of the United States, and resident of Freeport, in the county of Nassau and 5 State of New York, have invented certain new and useful Improvements in Type-writing Machines, of which the following is a specification.

The invention relates primarily to the 10 means for shifting the carriage or platen for upper case printing and locking the carriage in both its upper and lower positions. It has previously been proposed to lock 15 the carriage in its lower position through the shift key lever itself, as shown in my Patent No. 987,907, March 28, 1911. In such construction, however, the principle was embodied in a full size front strike 20 machine wherein the platen and carriage were given a substantially vertical shifting movement. The shift key lever and associated devices were positioned substantially in a horizontal plane.

25 The present invention is designed primarily for use in small compact portable machines and is shown as illustrated in the Royal portable machine. In this construction the platen has substantially an oblique movement, and necessities of space require 30 an entire reorganization of parts.

An object of the invention is to provide 35 means whereby the shift key lever directly locks the carriage in lower position and wherein the carriage may be released and moved by shift keys at each side of the machine.

Another object is to provide improved 40 means for locking the carriage in shifted position which means can be unlocked by pressure on the shift keys at either side of the machine.

A further object is to provide mechanism 45 for obtaining these and other results which will be compact and efficient and include a minimum number of parts.

Other objects of the invention will become apparent from a consideration of the 50 following detailed description and the appended claims.

In the drawings:

Figure 1 is a fore and aft section looking toward the left hand side of the machine.

Figure 2 is a top plan view of the left

hand side of the machine with parts removed.

Figure 3 is a side elevation with parts broken away and parts in section.

Figure 4 is a top plan view of the mounting of the shift key levers and associated parts.

The invention is disclosed in a machine of the portable type of the character illustrated in the application of Myers and Handley, Serial No. 757,169, filed Dec. 20, 1924, in which is disclosed and claimed the mounting of the carriage shift frame and adjusting means therefor. Since this mechanism forms no part of the present invention which in general may be employed with widely varying constructions, it will not be described in detail herein. Moreover, although the invention is of particular value in a small compact machine and has been especially designed therefor, it is not limited in its application thereto. Other instrumentalities such as the ribbon mechanism, type bar mechanism, etc., have no definite bearing on the invention and are merely shown to afford a more complete disclosure of the shifting means to the machine as a whole.

There is illustrated a main frame A provided with ribbon mechanism B, type bar C, character key levers D, space key E, carriage F with platen G, and a shift frame H. This shift frame is carried by plates I adjustably mounted in the frame A and supports a rock shaft K, the movement of which acts to shift the platen for upper case writing. A spring L acts as a counter-balance spring and stops N and O cooperating with offset ears P on the shift frame, limit the shifting movement in each direction. The parts thus far described are, or may be, the same as those disclosed in the application above mentioned and in themselves form no part of the invention herein claimed.

The shift frame H has at one side a 100 downwardly extending arm 1 having at its lower end an offset ear 2 provided with an adjustable stop screw 3. Intermediate its ends the arm 1 is provided with a headed stud 4 which is engaged by the hooked end 5 of a link 6 which is shown as extending 105 forwardly and then upwardly. The precise form of this link will depend upon the exi-

gencies of space or other considerations and may be varied so long as it suffices to transmit motion accurately from the shift key lever to the shift frame.

- 5 Members 7 attached to each side of the frame A have upturned ears 8 through which pass pivot screws 9 which support a shift shaft 10. A left hand shift key 11 is carried by a lever of peculiar shape clearly 10 illustrated in Figure 1. The portion 12 to which the key 11 is attached extends rearwardly in a horizontal plane to a point just in rear of the keyboard where it is provided with a downward extension 13 fast to the 15 shaft 10 and an upward extension 14 to which is hooked the front end of the link 6. From the rock shaft 10 the lever has a rearwardly extending portion 15 which is formed as illustrated to avoid interference 20 with other parts of the machine. This lever has an offset end 16 which contacts with the stop screw 3 when the parts are in normal position and thus locks the shift frame and platen in lower case or normal position. 25 All of the parts 12, 13, 14 and 15 are preferably integral and may be stamped out of one piece of sheet metal. Since the rock shaft 10 and the parts 12, 13, 14 and 15 are rigid and really form a single operative member, from one point of view these parts 30 12, 13, 14 and 15 may be regarded as extensions from the rock shaft or rocking frame. A shift key lever 17 at the right hand side of the machine is provided with a bushing 18 attached to the shaft 10 by a tapered pin 19. Both shift levers and the shaft therefore move as a unit and constitute a single element.

When either shift key is depressed the 40 shaft 10 is rocked and the rear end 16 of the left hand lever moves up quickly out of the path of the stop screw 3. This movement is permitted prior to the beginning of the movement of the shift frame by a slight 45 lost motion between the hook 5 and the stud 4 or at the forward end of the link where it connects with the arm 14. Continuation of the depression of the shift key will shift the 50 shift frame and platen to upper case position in the usual manner. The unlocking operation is also facilitated by the difference in lineal movement for a given angular movement between the end 16 of the shift lever and the point of attachment of the 55 link 6 to the extension 14.

A shift lock key 20 has a stem provided with a short forward extension pivoted at 21 to the portion 12 of the left hand shift key lever and normally drawn to the position shown in full lines in Figure 1 by a 60 spring 22 one end of which is attached to the stem of the lock key and the other end to the lever 12. The key stem also has a lip 23 which engages the under edge of the lever 12. It is also provided with a dwell

portion 24 near the key which engages a pin 25 when the key is depressed. This pin is carried by a portion 26 of the frame, and when the parts are in the dotted line position of Figure 1, the engagement of pin 25 with the dwell 24 holds the parts in shifted position. It is obvious that the shift lock may be released by a mere touch on either of the main shift keys, since a slight depression of the lever portion 12 frees the dwell 70 from the pin and permits the spring 22 to move the shift lock key to the full line position of Figure 1 relative to the main shift key lever.

There is illustrated a hollow sleeve 27 surrounding the shaft 10 between the left hand lever and the bushing 18 of the right hand lever. This has connected thereto the space key levers and has no relation to the shift mechanism. This compact organization of 75 parts is adapted to save space.

It will be apparent that the invention comprises a very compact relation of elements which are reduced in number to a substantial minimum. The shift frame is locked in lower position by the lever itself and in upper position by the shift lock lever. It is unlocked from either position by movement of either shift key. As previously 90 stated, it is particularly adapted to a machine of the type illustrated wherein the type bars occupy an oblique position at the movement of printing and the shift movement must be of a distinct type. The invention may be embodied in other types of machines and various elements may be modified in detail or used in other relations without departing from the spirit of the invention which is to be regarded as limited only 95 by the scope of the appended claims.

I claim as my invention:

1. In a typewriting machine, case shift mechanism comprising a shift frame having a depending arm, a shift key lever having engagement at its rear end with the lower end of said arm to lock the frame in normal position, and said lever also having a projection and a link connecting said projection with said arm intermediate its ends to move said frame.

2. In a typewriting machine, case shift mechanism comprising a shift frame having a depending arm, a shift key lever having a bent rear end to contact with the lower end of said arm to lock the frame in normal position, an upward extension on said lever intermediate its ends, and a link connecting said extension to said arm intermediate its ends.

3. In a typewriting machine, case shift mechanism comprising an obliquely movable shift frame having a depending arm, an adjustable contact member carried by said arm at its lower end, a shift key lever having a rear end engaging said contact

- member to lock the frame in normal position, an upward extension on said lever intermediate its ends and a link connecting said extension to said arm at a point above 5 said contact member.
4. In a typewriting machine, case shift mechanism comprising a shift frame having an arm, a rock shaft having a rearward extension contacting with said arm to lock 10 the frame in normal position, said rock shaft also having an upward extension for attachment of a connection to said arm for moving said frame by movement of the rock shaft, and means for rocking said 15 shaft.
5. In a typewriting machine, case shift mechanism comprising a shift frame, a rock shaft having a rearward extension engaging said frame to lock it in normal position, an upward extension on said rock 20 shaft, a link connecting said upward extension with the shift frame to move the same, and a forward key bearing extension to rock the shaft.
6. In a typewriting machine, case shift mechanism comprising a shift frame, a rock shaft having a rearward extension cooperating with said frame to lock it in normal position, an upper extension connected to 25 said frame to move the same, and a plurality of forward key bearing extensions to rock said shaft.
7. In a typewriting machine, case shift mechanism comprising a shift frame, a rock 30 shaft, and members connected to said rock shaft and engaging said frame at two different points, one member adapted to lock the frame in normal position and the other adapted to transmit power for moving the 35 same.
8. In a typewriting machine, case shift mechanism comprising a shift frame, a rock shaft, and two members connected to said rock shaft, one member engaging the frame 40 to lock the same in normal position, the 45 other member being connected to the frame at a different point, and the ends of said members being at different distances from the rock shaft whereby the end of the locking member has a much greater lineal 50 movement for a given angular movement of the rock shaft than does the other member.
9. In a typewriting machine, case shift mechanism comprising a shift frame, a 55 rocking frame having a rearward, an upward, and two forward extensions all moving as a unit, the rearward extension serving to lock the shift frame in normal position, the upward extension serving to transmit power for moving the shift frame, and the forward extensions being provided with 60 keys for moving said rocking frame.
10. In a typewriting machine, case shift mechanism comprising a shift frame, a 65 rocking frame having a rearward, an upward, and two forward extensions all moving as a unit, the rearward extension serving to lock the shift frame in normal position, the upward extension serving to transmit power for moving the shift frame, and the forward extensions being provided with 70 keys for moving said rocking frame, one of said forward extensions also carrying a 75 shift lock key, whereby the shift frame may be unlocked from either locked position by pressing either of the ordinary shift keys.
11. In a typewriting machine, case shift mechanism comprising a shift frame, shift key levers mounted on a pivoted shaft lying 80 considerably below the horizontal plane of the levers, one of said levers having an extension substantially in the horizontal plane of the shaft to lock the frame in normal position, and an extension to a point above 85 the horizontal plane of the key levers connected to the frame to move the same.

In testimony whereof, I have hereunto subscribed my name.

LEWIS C. MYERS
